[57] CLAIM

The ornamental design for a finished support, as shown.

DESCRIPTION

FIG. 1 is a top perspective view of the finished support.

FIG. 2 is a bottom perspective view thereof.

FIG. 3 is a top view thereof.

FIG. 4 is a left side view thereof.

FIG. 5 is a front view thereof, shown in its environment supporting an external air conditioner.

FIG. 6 is a bottom view thereof.

FIG. 7 is a bottom perspective view of the finished support shown in its environment supporting an external air conditioner.

FIG. 8 is a top perspective view of the finished support.

FIG. 9 is a bottom perspective view thereof.

FIG. 10 is a top view thereof.

FIG. 11 is a left side view thereof.

FIG. 11 is a front view thereof, shown in its environment supporting an external air conditioner.

FIG. 13 is a bottom view thereof; and,

FIG. 14 is a bottom perspective view of the finished support shown in its environment supporting an external air conditioner.

The broken line showing of an external air conditioner is for illustrative purposes only and forms no part of the claimed design.
